UNITED STATES PATENT OFFICE.

CLARENCE LEO BEST, OF SAN LEANDRO, CALIFORNIA, ASSIGNEE TO CATERPILLAR TRACTOR CO., OF SAN LEANDRO, CALIFORNIA, A CORPORATION OF CALIFORNIA.

TRACK-LAYING TRACTOR.

Application filed September 28, 1925. Serial No. 59,169.

This invention relates to improvements in track laying tractors, and more particularly to improved safety idler holding and automatic track tensioning means.

5 A serious difficulty in the operation of track laying tractors over sandy soil, gravel or sticky mud, is that the sprockets and tracks become plugged with hard packed dirt and tremendous tension is put on the tracks and associated parts, resulting in serious damage to the machine, the breaking of the front idler boxes or the tracks, the distortion of the truck frames, and causing disengagement of the tracks from the 10 wheels. It has heretofore been proposed to employ tensioning means in the form of springs interposed between abutments on the frame and the idler boxes and forcing the same forwardly with a yielding pressure, but such constructions are not practicable 15 for the reason that while upon forward movement the pull on the front idler wheel is slight, upon backward movement the pulling action is against the front idler, forcing the same back against the pressure of the 20 springs and slackening the track.

The object of the present invention is to 25 overcome the difficulty referred to; to provide improved idler holding and automatic track tensioning means of a simple, efficient 30 nature that will yield when the track is subjected to undue strain permitting the idler wheel bearing to move back and relieve the parts of strain; that will automatically move 35 the idler bearing forward to tighten the track as the excessive strain on the track is relieved, and which, at the same time, will 40 always maintain the track at the proper tension, in backing up as well as during forward movement.

The invention with other objects and advantages thereof, and the particular construction, combination and arrangement of parts comprising the same will be understood from the hereinafter contained detail description, when considered in connection with the accompanying drawings forming 45 part hereof, and illustrating one embodiment of the invention.

50 In the drawings:

Figure 1 is a side elevation of a tractor truck equipped with safety idler holding

automatic track tensioning means in accordance with the present invention.

Fig. 2 is a detail section, on the line 2—2 55 of Figure 3 with parts shown in elevation.

Fig. 3 is a top plan view of the front portion of the truck.

Fig. 4 is a side elevation of the structure illustrated in Figure 3. 60

Fig. 5 is a detail section on the line 5—5 of Figure 3.

Fig. 6 is a detail end elevation of one of the idlers and its bearing boxes, the side frame members of the truck being shown in 65 section.

Fig. 7 is a detail top plan view of one of the idler shaft bearing boxes and the friction brake associated therewith.

Fig. 8 is a detail side elevation, with parts 70 shown in section, of the idler shaft bearing box structure illustrated in Figure 7.

The invention contemplates improved safety idler holding and automatic track tensioning means including spring pressure 75 tensioning means in combination with a friction brake for retarding the movement of the idler box, and which acting in conjunction with the spring tensioning means, will maintain the idler in operative position with 80 the track under proper tension when the tractor is backing up under full power, while at the same time, being adapted to yield permitting the idler bearing to move back to relieve excessive strain, as when the parts 85 become plugged with dirt, and to move up the idler bearing to maintain the track tight as the dirt works free from the track and sprocket.

While a preferred embodiment of the invention is illustrated in the drawings, it 90 will of course be understood that changes and variations in the particular construction shown, and the embodiment of the invention in other forms, as will appeal to those 95 skilled in the art and falling within the scope of the appended claims, may be practiced without departing from the spirit of the invention.

In the drawings, the invention is shown 100 applied to one of the well known forms of tractor trucks, the same comprising spaced parallel channels 1 suitably secured together, an endless tread 2, a rear driving sprocket 3.

mounted in bearings 4 fixedly secured to the channels 1, and a front idler surface or wheel 5. 6 and 7 designate the supporting rollers or wheels for the endless track 2.

5 In accordance with the present invention the front idler wheel 5 is slidably supported on the truck frame channels 1. In the particular construction shown, the idler 5 is rotatably mounted upon a short axle 8 secured by screws 9 in boxes 10 slidably mounted upon the channels 1. Each of the boxes 10 comprise a cylindrical bearing part 11 for the axle 8, a lower horizontal plate part 12 having a flat bottom face to engage the upper face of the upper flange 1^a of one of the channels 1, with a portion 13 at its inner side to fit against the inner side of the channels 1, and at its other side, an extension 14 extending around and under 20 the upper flange 1^a of the channel to hold the box 10 thereon against lateral displacement while permitting the same to slide thereon (see particularly Figures 2 and 6 of the drawings). In the particular exemplification of the invention illustrated in the drawings, the portion 13 at the inner side of the bottom plate 12 of the box 10 is formed by the lower part of an inner annular flange or collar 15 which is adapted 25 to fit over a hub part 5^a of the idler wheel 5. The extension 14 takes the form of a separate plate member detachably connected to the main part of the axle box 5 by bolts and nuts 16, 17, the bolts 16 extending vertically through openings in the bottom plate part 12 and bosses 18 on the upper side thereof.

The yieldable idler holding and track tensioning means includes coiled springs 19, 40 each spring being interposed between and bearing at opposite ends against a depending lug 20 on one of the axle boxes 10, and an abutment 21 on one of the truck frame channels 1, and being supported on a rod 45 22 which at one end slidably engages an aperture 23 in the depending lug 20, and at its other end has an adjustable threaded connection with the abutment 21. Each abutment 21 is shown in the form of a bracket suitably secured to one of the channels 1 by bolts and nuts 24, 25, or equivalent means, and having an outstanding abutment part in the form of a split nut 21^a provided with a clamp screw 21^b, the rods 22 55 each having at one end a threaded portion 22^a adjustably engaging one of the split nuts 21^a. As will be understood by turning the rods 22 through the heads 22^b on the outer ends thereof, the tension of the springs 19 60 can be adjusted.

Each of the idler axle boxes 10 is provided with friction brake mechanism to cooperate with the spring pressure mechanism to yieldably hold the boxes in place, said friction brake mechanism operating against a

surface of the truck frame channels 1. Each journal box 10 is shown provided with a pair of friction brake devices located thereon near the ends of the flat plate part 12 thereof at either side of the cylindrical 70 journal part 11. Each friction brake device comprises a spring pressed brake element engaging the upper face of the upper flange 1^a of one of the frame channels 1. 26 designates the brake element and 27 coiled 75 springs pressing the brake elements 26 against the channels 1, the same being supported in vertically extending chambers 28 on the journal boxes, said chambers 28 being open at their lower ends and having closed 80 upper ends against which the upper ends of the coiled springs 27 abut. The brake elements 26, which take the form of circular plates, may be constructed of mild steel or other material suitable for the purpose. 85

The friction brake mechanism of the idler bearing boxes 10 is adapted to exert sufficient retarding or braking force to maintain the idler box in position with the track under proper operative tension when the tractor is 90 backing up under full power. If the track plugs it must plug so tight that it comes under tension of several thousand pounds before it overcomes the friction brake mechanism and the tension of the springs 19. 95 At this stage, the front idler wheel 5 snaps back and relieves the excessive strain or tension. Under these circumstances while the excessive strain and tension is relieved, the track is maintained tight and operating 100 in this way the tendency is for the track to free itself of the dirt, and as soon as this takes place, the front idler snaps forward to maintain the track tight.

It will be noted that the friction brake 105 mechanism operating in conjunction with the spring pressure means affords idler holding and automatic track tensioning means of a simple, efficient nature providing for maintaining the track under proper operative tension on backing up under full power as well as upon forward movement, and, at the same time, provides for yielding or backward movement of the idler wheel to relieve the parts of undue strain when 110 the track becomes plugged with dirt. 115

What I claim is:

1. In a track laying tractor, a truck frame, an endless track, a driving sprocket and an idler for the track, a bearing for the idler 120 slidably mounted on the frame, and yieldable means for holding the said idler bearing in place on the frame, said means including spring tensioning means in combination with a friction brake.

2. In a track laying tractor, a truck frame, an endless track, a driving sprocket and an idler for the track, a bearing for the idler 125 slidably mounted on the frame, and yieldable means for holding the said idler bearing 130

in place on the frame, said means including a spring tensioning means in combination with a friction brake, said friction brake comprising a spring pressed brake element on the 5 idler bearing arranged to engage a part of the truck frame.

3. In a track laying tractor, a truck frame, an endless track, a driving sprocket and an idler for the track, a bearing for the idler 10 slidably mounted on the frame, and yieldable means for holding the said idler bearing in place on the frame, said means including spring tensioning means in combination with a friction brake, said friction brake comprising 15 a chamber on the idler bearing open at one end at the bottom face of the bearing, a brake block slideable in the lower end of said chamber, and a coiled spring in the chamber back of said block pressing the same against 20 a part of the truck frame.

4. In a track laying tractor, a truck frame, an endless track, a driving sprocket and an idler for the track, journal boxes for the idler wheel slidably mounted on the frame, 25 yieldable means for holding the idler wheel journal boxes in place on the frame, said means including a coiled spring associated with each of the journal boxes to press the same forwardly, and a spring pressed friction brake device on each journal box arranged to engage a part of the frame, 30

5. In a track laying tractor, a truck frame, an endless track, a driving sprocket and an idler wheel for the track, journal boxes for

the idler wheel slidably mounted on the 35 frame, yieldable means for holding the idler journal boxes in place on the frame, said means including a coiled spring associated with each of the journal boxes to press the same forwardly, and a pair of spring pressed friction brake devices located on each journal box near either end thereof and arranged to engage a part of the frame. 40

6. In a track laying tractor, a truck frame, comprising spaced parallel bars each having 45 a lateral flange, an endless track, a driving sprocket and idler wheel for the track, journal boxes for the idler wheel each slidably mounted on the flange of one of the frame bars at the upper side thereof and having 50 an extension part to slidably engage the flange at the under side thereof, and yieldable idler holding and track tensioning means including coiled springs to exert pressure longitudinally upon the idler journal 55 boxes, in combination with a friction brake for each idler journal box comprising a brake element arranged to engage the flange of one of the frame bars at the upper side thereof, and a spring interposed between 60 the brake element and a part on the idler journal box and pressing the brake element downwardly against the upper face of the flange.

In testimony whereof I hereunto affix my 65 signature.

CLARENCE LEO BEST.
